5 Claims. (Cl. 23—88)

This invention relates to the production of stannous fluoride from the combination of tin and hydrofluoric acid and refers more particularly to such a method wherein the hydrofluoric acid may be added to a mass of the metallic tin.

This application is a continuation-in-part of our application Serial No. 610,890, filed September 20, 1956, entitled "Method of Producing Stannous Fluoride," now Patent No. 2,924,508.

Stannous fluoride is presently of great commercial interest as an additive for dentifrices to supply fluorine values to human teeth for the purpose of reducing the incidence of dental caries.

The only method for making stannous fluoride given in the literature involves the dissolution of stannous oxide in aqueous hydrofluoric acid. This reaction has been developed so as to be able to obtain therefrom high purity stannous fluoride of the character required to investigate its character in minimizing dental caries incidence. However, in this reaction, conditions of concentration, temperature and other factors have proved to be of the utmost importance in obtaining a complete interaction of the two reactants. It has also been found quite easy to miss the ideal conditions and, in such case, the stannous oxide would not be completely dissolved in the acid. Even under the best conditions in this reaction, it is usually necessary to clarify the solution in order to obtain from it a white, pure salt of stannous fluoride.

In addition to the apparent criticality in conditions for the reaction, other disadvantages have been encountered in the dissolution of stannous oxide in hydrofluoric acid. Filtration of the solutions frequently is difficult and slow. The cost of tin in the form of stannous oxide is relatively high. For example, we have recently priced stannous oxide at \$1.84 per pound for the tin in comparison to a tin metal price of \$1.00 per pound. Additionally, the available commercial sources of stannous oxide are severely limited as compared to the ready sources of metallic tin.

Because of the above many objections regarding the use of stannous oxide in making stannous fluoride, we have sought an alternative method of preparation of stannous fluoride. Tin, being above hydrogen in the electromotive series of the metals, theoretically should be soluble in acids to liberate hydrogen and to leave a salt of the metal and the anion of the acid. In view of this, we considered the possibility of making stannous fluoride by dissolving metallic tin in hydrofluoric acid. Literature research, however, clearly indicated that such a method was impractical. Not only are all of the methods described in the literature for the production of stannous fluoride specific in designating the use of stannous oxide, but, also, many statements in standard literature references indicate the futility of attempting to prepare stannous fluoride directly from metallic tin.

In our patent application Serial No. 610,890, above, we were able to demonstrate the error in the literature both in regard to the reactivity of substantially anhydrous

2

hydrofluoric acid and tin and the solubility of stannous fluoride in substantially anhydrous hydrofluoric acid. In Serial No. 610,890, we demonstrated that, by maintaining the temperature of the reaction, substantially, at least below the melting point of tin, liquid, substantially anhydrous hydrofluoric acid and finely divided metallic tin could be reacted to produce stannous fluoride. In this application, as well, we disclosed a method of adding the finely divided metallic tin to an excess of liquid hydrofluoric acid in measured quantities to produce the stannous fluoride. Experience proved that while the latter method was operable commercially, it would be desirable for a number of reasons to have an operative method of adding the acid to the tin instead of vice versa. The problems of control of the reaction temperature below the melting point of tin, however, were far more severe.

Therefore, an object of the invention is to provide a method of reacting metallic tin and hydrofluoric acid which permits the production of stannous fluoride upon a commercial scale and of high purity.

Another object of the invention is to provide a method of producing stannous fluoride by the addition of hydrofluoric acid to a mass of finely divided metallic tin.

Another object of the invention is to provide a method of reacting metallic tin and hydrofluoric acid to produce stannous fluoride by reacting the metallic tin in an excess of acid, wherein, although the acid is added to the tin, agglomeration of the metallic tin and fusing thereof is completely avoided.

Another object of the invention is to provide a method of reacting metallic tin in an excess of hydrofluoric acid to produce stannous fluoride wherein the separation of excess acid from the reaction product is easily and simply accomplished and the separation of the stannous fluoride as crystals from the acid is also easily accomplished.

Another object of the invention is to provide a method of reacting metallic tin in an excess of hydrofluoric acid in a first reaction step to produce stannous fluoride wherein the excess acid is recycled to a second reaction step with further tin, a portion of the stannous fluoride produced in the original reaction employed as a solution to aid in the separation of newly produced stannous fluoride from the second reaction step.

Yet another object of the invention is to provide a method of producing stannous fluoride by the reaction of metallic tin and hydrofluoric acid, wherein the close control of the temperatures of the tin and the reaction step permits considerable variance in other variables of the reaction, thereby reducing the criticality of the reaction, yet not sacrificing the purity of the product.

Another object of the invention is to provide a method of controlling critical temperatures in the reaction of hydrofluoric acid and metallic tin to produce stannous fluoride whereby all of the tin may be reacted in an excess of acid and local fusing and agglomeration of the tin due to excess heating in the reaction step is completely avoidable.

Other and further objects of the invention will appear in the course of the following description thereof.

60 In the drawing, which forms a part of the instant specification and is to be read in conjunction therewith, an embodiment of the invention is shown in the form of a schematic flow diagram of a portion of the inventive process.

65 Referring to the schematic flow diagram, at 10 is shown a reaction vessel having input fittings 11 and 12 which may be sealed, heat exchanging jacket 13 with input and output connections 14 and 15, and bottom discharge fitting 16. Reflux condenser 17 has heat exchange medium input and output fittings 18 and 19. Flow line 20 carries hydrogen gas and hydrofluoric acid vapors to the reflux condenser and withdrawal line 21

carries hydrogen gas to the scrubber. Flow line 22 controlled by valve 23 passes condensed hydrofluoric acid from the reflux condenser to receiving tank 24 from which flow line 25, controlled by valve 26, returns the acid to the reactor.

The process of the reaction of the tin with the acid in vessel 10 will now be described. The seal on fitting 12 is removed and a charge of relatively finely divided metallic tin is poured into the reactor. The seal is then replaced and the tin is cooled by circulating cold brine or other low temperature heat exchanging medium through the jacket 13 which surrounds the lower part of the reactor. With the reactor and the tin cooled to at least a temperature below the boiling point of the hydrofluoric acid at the pressures of the reaction step and preferably to about -15° C. , concentrated hydrogen fluoride is added as rapidly as it will drain from the cylinder. The reaction initially is rather slow but, as the temperature comes up to the boiling point of the hydrogen fluoride, the velocity of the reaction increases, but never to an undesirable or uncontrollable extent. No trouble is encountered from hydrogen evolution producing a froth which is carried out of the reactor. Reflux condenser 17 cools the evolved vapors of hydrogen and acid and returns the condensed hydrogen fluoride to the reactor via receiving tank 24. The hydrogen is passed through a scrubbing tower to remove any trace of hydrogen fluoride escaping the reflux condenser 17. The interaction of the tin and hydrogen fluoride with the production of hydrogen will produce adequate mixing so a mechanical mixer is not required. However, if it is desired to speed up the completion of the reaction, such mechanical mixing will aid, as the reaction otherwise slows down a good deal after an hour or two. A typical time schedule for a charge of 250 pounds of powdered tin and 400 pounds of anhydrous hydrogen fluoride, without mechanical mixing, requires a reaction time of about four hours after bringing the two reactants together. After this time, the hydrogen fluoride may be vaporized out as will be described later.

It should be pointed out that a most critical factor in the reaction is to maintain at least substantially the entire reaction step at a temperature below the melting point of the tin. The tin itself must be relatively finely divided and must not be permitted to accumulate enough heat in the exothermic reaction to bring the mass up to its fusion temperature. When the tin powder is placed in the reactor first and cooled, the hydrogen fluoride does not react rapidly when it first strikes the tin and, before sufficient heat is produced by the reaction to cause this trouble, the volume of hydrogen fluoride in the reactor is sufficient to serve as a coolant. Heat of reaction is dissipated through evaporation of the hydrogen fluoride. To prevent excessive vaporization loss of hydrogen fluoride the reactor is equipped with the cold reflux condenser. The addition of the hydrogen fluoride preferably takes place within a matter of 15 minutes and may be added partly from a tank retaining the residual amount from the preceding run and partly fresh acid. Once the hydrogen fluoride, in the quantity desired, has been added to the reactor, the brine is drained from the jacket 13 so that the temperature within the vessel comes up to the boiling point of hydrogen fluoride at the reaction pressure (19.4° C. at atmospheric). The total quantity of hydrogen fluoride in the reactor at all times, as controlled by the amount of recycle from the reflux condenser, must be sufficient to maintain the temperature of the reaction below the melting point of tin.

When hydrogen evolution becomes slow, the near completion of the reaction is indicated. The reaction may be completed within three to four hours depending on various factors to be set forth. After completion of the dissolution of the tin, steam may be passed through the jacket 13 and the excess hydrogen fluoride vaporized and collected in the receiving tank 24 maintained for that

purpose. Evaporation of the solution is continued until the liquid is at a temperature of about 65° C. , at which point it retains 8 to 10% hydrogen fluoride which is necessary to maintain fluidity which permits a clean discharge from the reactor.

The discharged strong solution is received in an aqueous stannous fluoride solution, the filtrate from a preceding batch of crystals, or in an auxiliary closed, jacketed tank of an alloy resistant to both aqueous and anhydrous hydrogen fluoride from which the remaining hydrogen fluoride is vaporized. In the first case the majority of the stannous fluoride from the reactor precipitates out in the aqueous solution until the whole is heated whereupon the salt is dissolved. The excess hydrogen fluoride in the solution is neutralized with stannous oxide and the solution is filtered and cooled to crystallize out the pure salt.

If the reactor is discharged into an auxiliary jacketed tank the mixture of stannous fluoride and hydrogen fluoride is heated further to drive off additional hydrogen fluoride. The solid remaining is then taken up in hot aqueous stannous fluoride solution circulated through this auxiliary tank, which solution may be the filtrate from a preceding batch of crystals.

As an alternative method of recovering the stannous fluoride from the excess hydrogen fluoride remaining in the reactor after completion of the reaction, the contents of the reactor may be cooled sufficiently to crystallize out the stannous fluoride. The residual solution then may be decanted or otherwise removed from the crystalline stannous fluoride remaining in the reaction vessel and employed, if desired, for further use in the system by addition of an appropriate quantity of fresh hydrogen fluoride, if needed.

We have found the concentration of the acid to be critical within a certain range. With the tin powder initially at -15° C. , and with acid added to give a 5 to 1 acid-tin molar ratio (stoichiometric ratio 2 to 1), in a four hour period, anhydrous acid gave a 100% complete reaction, 90% acid gave 95% completion, and 75% acid gave 54% completion. We have observed slow reaction of tin and acid at concentration of acid as low as 50% but not at lower concentrations. At 90% acid concentration, we have found that, in sixteen hours, we can get all of the tin dissolved, that is, we have 100% completion. Thus, concentrations are important in determining the rate of reaction; anhydrous acid gives the highest rate. A minimum acid concentration of 50% appears to be required for any measurable reaction.

In our application Ser. No. 610,890, we disclosed the reaction of tin and substantially anhydrous hydrofluoric acid, preferably in a process of adding finely divided tin to an excess of acid. We have discovered that this latter process can be performed, though not as successfully and quickly, as when employing more concentrated acid, with hydrogen fluoride in a concentration as low as 50%. Adequate reaction, however, is best achieved in the addition of tin to acid in the process of Ser. No. 610,890 with the substantially anhydrous acid of over 70% concentration.

We have found the ratio of acid to tin also affects the rate of completion of the reaction. Employing anhydrous hydrofluoric acid added to cold tin powder, a ratio of 5 mols of acid to 1 mol of tin gave 100% dissolution of the tin in two hours, 4 mols acid to 1 mol tin 97% completion in the same period, 3 mols acid to 1 of tin 95.5% completion and 2.5 mols acid to 1 of tin 63% completion in a like period. The reaction is conductable with slightly over the stoichiometric amount of acid relative the tin but the optimum ratio is at least four mols acid per mol of tin.

We have found the temperature at the time of bringing the reactants together to be another critical factor. We have found the upper limit for an effective reaction to be the temperature above which the finely divided tin ag-

glomerates so as to reduce its surface area to a low value. Such agglomeration may consist of a slight sintering of the tin to give a somewhat less reactive mass or it may be a complete fusing so that a compact mass of metal is obtained which dissolves very slowly. When the tin powder is added to a large volume of anhydrous hydrofluoric acid, as in our previous application supra, the liquid acts as a coolant and the hydrogen evolved acts as a means of mixing. Under these latter conditions, the metal does not approach its fusion point because the hydrofluoric acid remains at or near its boiling point. However, when the acid is added to the tin, an initial reaction may take place before enough liquid is present to maintain the tin temperature below its softening point. We have prevented such undesirable overheating by the cooling the metal before adding the acid. When the temperature of the tin was reduced to -15° C . before addition of the acid (in the ratio of 5 mols acid to 1 of tin), the tin dissolution was 100% completed in two hours. When the tin was cooled to 0° C . before adding the acid, with the same ratio of reactants, the reaction was 94% complete in two hours. When the tin was cooled to 19.4° C . (the boiling point of the acid at atmospheric pressure) at the same ratio of reactants, 83% reaction occurred in two hours. The most important thing is to prevent localized heating from the reaction. In practice, the optimum pre-cooling is to -15° C .

As to the temperature during the reaction, we have found that the allowable temperature to be attained in the reaction mixture must be governed by the same general requirement as set forth previously, namely, the metal must not be permitted to reach, even at localized spots, the temperature where it will fuse together. The optimum reaction conditions employ anhydrous hydrofluoric acid with the temperature controlled by acid recycle to remain at the boiling point of this liquid at atmospheric pressure. However, we have operated at superatmospheric pressures and elevated temperatures below the melting point of the tin with 75% concentration acid and have had reasonably good results.

As to the size of the particles, it is very difficult to indicate a nonreactive limit to the size of particles. A tin powder which passes 99% through 325 mesh is preferable because of its high rate of dissolution. A powder which passes 94% through 325 mesh is workable but slower in reaction. The reaction is very slow with -20 mesh tin granules. Clearly, the particle size relates primarily to the desired reaction rate.

The reflux condenser 17 preferably should be operative to cool the evolved gases passing thereto from the reactor 10 to a temperature of -15° C . or below, whereby to adequately inhibit untimely escape of the hydrofluoric acid from the reaction chamber although affording to evolved hydrogen a relatively free exit therefrom. The condenser discharge passage into flow line 20 must be of sufficient capacity to allow for escape of the gaseous acid as well as the hydrogen evolved from the reaction. The return by gravity of relatively cold liquid hydrofluoric acid from the reflux condenser, when the latter is kept at -15° C . or below, tends to counteract the heat generated in the exothermic reaction which otherwise might proceed with considerable violence if this or some other expedient were not employed for preventing overheating in the reaction vessel. The acid boils at about room temperature (19.4° C .) at atmospheric pressure and the reaction readily proceeds at approximately the slightly higher boiling point of the reacting mass when the conditions described above are maintained. Condensation of vaporized acid, together with cooling of escaping hydrogen, extracts from the system primarily only heat generated by the exothermic reaction.

It is evident to those skilled in the art that under certain conditions hydrogen fluoride is highly corrosive to materials of construction. In addition to the advantages already enumerated regarding the use of highly concen-

trated hydrogen fluoride, a great convenience and economy is found in use of this reagent as ordinary steel can be employed for construction of reacting equipment when the HF concentration is above 70%. Aluminum may be satisfactorily used also, but it is more sensitive to the presence of water and consequently cannot be used in concentrations of hydrogen fluoride lower than about 95%. We have found also that polyethylene, silver and platinum are satisfactory for carrying out this reaction and the observation that these various materials of construction can be used tends to negative the possibility that the reacting vessel has any catalytic effect in the reaction between the tin and hydrogen fluoride, which reaction it has heretofore been thought could not be carried to completion in respect to either the tin or hydrogen fluoride.

It is believed our discovery that stannous fluoride is soluble in an excess of concentrated hydrofluoric acid at about its boiling point has contributed materially to the success of our method in that by virtue of the solubility of the reaction product (SnF_2) in the acid, the formation of the product in the reaction does not prevent continued reaction of the tin. If SnF_2 were insoluble in the acid, it would be expected to deposit at the site of production, that is, on unreacted tin, and thereby materially retard the dissolution of the remaining metal.

As the crystalline product obtained by the practice of our method is soluble in cold water, it is apparent that it may be added to dentifrices in the manufacture thereof by any suitable or desired procedure in the proportions deemed appropriate for presenting on contact with the teeth of the consumer a proper concentration of a fluorine bearing compound, nontoxic at concentration employed but adequate to reduce the incidence of dental caries, about .4% stannous fluoride in toothpaste and comparable concentrations in other forms of dentifrices usually being considered adequate and not injurious to the health of the user.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter hereinabove set forth or shown in the accompanying drawings is to be interpreted as illustrative and not in a limiting sense.

Having thus described our invention, we claim:

1. A method of producing stannous fluoride comprising the steps of first cooling a quantity of relatively finely divided metallic tin to a temperature substantially below the boiling point of hydrofluoric acid at the pressures of the reaction step, said tin cooled to a temperature sufficiently below the boiling point of liquid hydrofluoric acid at the pressures of the reaction step to substantially prevent any reaction of the tin upon contact with liquid hydrofluoric acid, then adding a quantity of liquid hydrofluoric acid of greater than 50 percent concentration to said tin in a reaction step, then permitting the temperature of the reaction mixture to rise to the temperature of the boiling point of the solution at the pressures existing in the reaction step whereby to permit the reaction of the tin and the acid, maintaining the reaction step at least substantially in its entirety at a substantially uniform temperature not greater than the boiling point of the liquid present in the reaction step, by maintaining a sufficient excess of liquid hydrofluoric acid continuously present in the reaction step and in contact with at least substantially all of the tin reacting in the reaction step, whereby to prevent at least substantially any agglomeration of the tin into unreactive metallic bodies in said reaction step due to fusion thereof in the presence of excess heat, and

recovering stannous fluoride from the resultant solution.

2. A method of producing stannous fluoride by contacting tin and hydrofluoric acid in the reaction step comprising the steps of first cooling a quantity of relatively finely divided metallic tin to a temperature substantially below the boiling point of hydrofluoric acid at the pressures of the reaction step, said tin cooled to a temperature sufficiently below the boiling point of liquid hydrofluoric acid at the pressures of the reaction step to substantially prevent any reaction of the tin upon contact of liquid hydrofluoric acid therewith, then adding a quantity of liquid hydrofluoric acid of greater than 50 percent concentration to said tin, the quantity of hydrofluoric acid added being in excess of the molar quantities represented by the equation:

then permitting the temperature of the reaction mixture to rise to the temperature of the boiling point of the solution at the pressures existent in the reaction step whereby to permit complete reaction of the tin and acid, maintaining a sufficient quantity of hydrofluoric acid present at all times in the reaction step and in contact with at least substantially all of the tin reacting in the reaction step, so as to maintain the reaction step at least substantially in its entirety at a substantially uniform temperature not greater than the boiling point of the liquid present in the reaction step, said hydrofluoric acid in excess of the amount of hydrofluoric acid required to dissolve the tin, whereby to prevent at least substantially any agglomeration of the tin into unreactive metallic bodies in said reaction step

due to fusion thereof in the presence of excess heat, and recovering stannous fluoride from the resultant solution.

3. A method as in claim 2 wherein the step of recovering stannous fluoride from the resultant solution includes raising the temperature of the reaction mixture after completion of the reaction above the boiling point of the acid whereby to vaporize a quantity thereof and removing said vapor from said reaction step.

4. A method as in claim 3 including the step of discharging the acid-stannous fluoride mixture after removal of said vapor into an aqueous solution of stannous fluoride to precipitate stannous fluoride crystals.

5. A method as in claim 3 including the steps of discharging the acid-stannous fluoride mixture after removal of said vapor into an aqueous solution of stannous fluoride to precipitate stannous fluoride crystals, neutralizing the mixture of the aqueous solution of stannous fluoride and acid solution by reaction of the acid with stannous oxide and then cooling same to crystallize out stannous fluoride.
